US00D966660S

(12) United States Design Patent (10) Patent No.: US D966,660 S
Harris et al. (45) Date of Patent: * Oct. 18, 2022

(54) SHIRT

(71) Applicant: NIKE, Inc., Beaverton, OR (US)

(72) Inventors: Charlotte Harris, Portland, OR (US);
Erick Lopez, Beaverton, OR (US);
Brianna Vizcaino, Beaverton, OR (US)

(73) Assignee: NIKE, Inc., Beaverton, OR (US)

() Term: 15 Years

(21) Appl. No.: 29/819,953

(22) Filed: Dec. 17, 2021

(51) LOC (13) Cl. 02-02

(52) U.S. Cl. USPC D2/840

(58) Field of Classification Search

USPC D2/840, 717, 742, 731; D5/53

CPC A41D 1/04; A41D 13/0015

See application file for complete search history.

(74) Attorney, Agent, or Firm — Banner & Witcoff, Ltd.

(57) CLAIM

The ornamental design for a shirt, as shown and described.

DESCRIPTION

FIG. 1 is a front perspective view of a shirt showing our new design;

FIG. 2 is an opposite side front perspective view thereof;

FIG. 3 is a rear perspective view thereof;

FIG. 4 is an opposite side rear perspective view thereof;

FIG. 5 is a front view thereof;

FIG. 6 is a rear view thereof;

FIG. 7 is a side view thereof; and,

FIG. 8 is an opposite side view thereof.

The broken line immediately adjacent to the photographic area defines the bounds of the claimed design and forms no part thereof. The broken lines depicting the remainder of the shirt form no part of the claimed design.

1 Claim, 8 Drawing Sheets
